US00D691569S

(12) **United States Design Patent**
Edmond et al.

(10) **Patent No.:** **US D691,569 S**
(45) **Date of Patent:** **** Oct. 15, 2013**

(54) **LED CHIP**

(75) Inventors: **John A. Edmond**, Durham, NC (US);
Michael J. Bergmann, Chapel Hill, NC (US);
Matthew Donofrio, Raleigh, NC (US);
Winston T. Parker, Cary, NC (US)

(73) Assignee: **Cree, Inc.**, Durham, NC (US)

(**) Term: **14 Years**

(21) Appl. No.: **29/388,240**

(22) Filed: **Mar. 25, 2011**

(51) LOC (9) Cl. **13-03**

(52) U.S. Cl.

USPC **D13/180**

(57) **CLAIM**

The ornamental design for a LED chip, as shown and described.

DESCRIPTION

FIG. 1 is a top perspective view of an LED chip showing our design;

FIG. 2 is a top view thereof;

FIG. 3 is a first side view thereof;

FIG. 4 is a bottom view thereof;

FIG. 5 is a different side view thereof;

FIG. 6 is an end view thereof;

FIG. 7 is an opposing end view thereof;

FIG. 8 is a top perspective view of the LED chip of FIG. 1 with the top surface removed;

FIG. 9 is a top view thereof;

FIG. 10 is a first side view thereof;

FIG. 11 is a bottom view thereof;

FIG. 12 is a different side view thereof;

FIG. 13 is an end view thereof; and,

FIG. 14 is an opposing end view thereof.

The broken lines are for illustrative purposes only and form no part of the claimed design.

1 Claim, 4 Drawing Sheets
